METHOD OF MAKING ELECTRICAL CONTACTS
Childress B. Gwyn, Jr., Export, Pa., assignor, by mesne assignments, to Tacon, Inc., a corporation of Pennsylvania

Filed Sept. 26, 1961, Ser. No. 140,835
1 Claim. (Cl. 29—155.55)

This invention relates to electrical contacts and more particularly to a method of making contacts for projection welding in electrical assemblies.

In my prior patents, Nos. 2,049,771 and 2,199,240, there are shown methods of making electrical contacts having certain cost advantages wherein the method used is known as "puddling." In this method a base metal subhead, of disc shape, is used on which a segment of precious metal, for example, silver or the like is placed and subjected to heat. Thus, the precious metal melts and flows to form a contact facing for the subhead. The subhead may be of low carbon steel or the like, and can be produced by cold heading. Suitable fluxes or platings can, of course, be applied to the subhead so that upon melting of the silver segment the resulting molten silver coating adheres to the subhead. The method is fairly economical as compared with methods known in the art prior to my patents, which methods required fabrication of laminated strips and subsequent punching or coining with attendant waste due to scrap loss and/or costly reclamation of precious metal therefrom.

However, the puddling methods disclosed in my prior patents have certain drawbacks due to the fact that the melted silver hardens into a convex meniscus of semi-hemispherical shape, producing a product which is disproportionately high at the center of the contact face. Also, variations in coating height from contact to contact occur, due to variations in actual composition of the silver and variations in surface tension thereof when melted, as well as to variations in original dimensions of the silver segments. Thus, the height of the silver facing produced by the ordinary puddling process is many times greater at the center than at the outer edge of the subhead. Further, a thinning or ragged feathering of the facing occurs at such edge and sometimes the subhead surface adjacent the edge is not coated by the silver. Subsequent coining can not correct the condition insofar as the raggedness of or scalloping of the coating at the periphery of the subhead is concerned.

It is, therefore, an object of the present invention to improve the puddling method and effect an electrical contact for projection welding which eliminates the above noted drawbacks and which produces a product that is completely uniform and electrically and mechanically sound.

Other objects and devices of the invention will be apparent from the appended drawing and from the description to follow:

Briefly my invention comprises the providing of a steel subhead disc-like, copper or otherwise plated, and having a raised concentric plateau on one side, or on both sides. A silver segment is placed on either plateau and heated to the melting point of the silver at which time it fuses as a coating on the face of the plateau and down the sides of the plateau and covers the surrounding marginal surface of the subhead to the edges thereof. Subsequent coining then flattens the silver coating at the center and across the edges of the subhead to produce a completely integrated contact element having uniformly coated edges. Thus, the coining process and the pressure applied flattens the plateau beneath the coating into intimate contact therewith, while at the same time a welding projection is formed.

2

In the drawing:

FIGURES 1 through 5 show various steps in the prior art puddling process.

FIGURES 6 through 10 show the steps of the improved process; and

FIGURE 11 shows a modified type of subhead which may be used.

Referring now to the prior art process of FIGURES 1 through 5, FIGURES 1 and 2 show plan and side views, respectively, of a subhead disc 10 on which has been placed a precious metal cylindrical wire segment 13, such as silver or the like.

FIGURE 3 shows a cross-section of the composite article after the silver 13' has been melted to flow across the face of the disc 10. It will be noted that there is a high spot in the center which is many times the thickness of the coating at the periphery or edges 14. At times the edge coating may be as low as .003 inch to .006 inch. Subsequent coining produces the effect shown in the cross-section of FIGURE 4, with the welding projection 16, wherein the center height of the silver coating 13" has been reduced to that which is desired, but wherein the coating thickness at the edges is not uniform nor even fully extending to the edges of the subhead in many instances. Thus, in the plan view of FIGURE 5, the ragged or scalloped and uneven effect is illustrated. This condition cannot be corrected by change of shapes of coining tools, at least not to a satisfactory degree.

Referring now to FIGURES 6 through 10, the improved process and article is illustrated wherein it will be noted that a subhead disc 20 is provided with a concentric inner protuberance or plateau 23 leaving a marginal recessed area 26 from the base of the plateau to the edges 28 of the subhead. A silver segment 30 placed upon the plateau 23, when melted, will flow to assume the condition 30' as seen in FIGURE 8. It will be noted that the entire top surface of the subhead is covered and that the silver has flowed down the sides of the plateau and across the marginal area 26 to the very edges of the subhead 20. Thus, the slight rise in height afforded to the molten silver by the plateau effects a shaping of the molten mass to give a gravity or capillary assist which aids in flow down the sides of the plateau and out to the edges of the subhead, substantially filling the recess 26 between the plateau and the subhead edges. It will further be noted that the thickness of the coating is considerably greater toward and at the subhead edges as compared with the prior art puddling process at this step, for example, as seen by comparison with FIGURE 3.

The further step of coining achieves the effect of flattening the plateau beneath the coating and squaring off the coating at the subhead edges, as illustrated in the cross-section of FIGURE 9 and the plan view of FIGURE 10. Thus, unevenness or scalloping, or lack of coating, are eliminated.

The modification shown in FIGURE 11 shows a subhead 40 having a plateau 43 on each side thereof. Such modification may be handled in mass production without regard to orientation for purposes of bringing a particular subhead face into upward position. In other words, the silver may be applied to either plateau in the manner illustrated and described hereinabove.

The welding projection (not shown) would be produced on the lower side of the subhead during coining.

Having thus described my invention, I am aware that various changes may be made without departing from the spirit thereof, and, therefore, do not seek to be limited to the precise illustration herein given, except as set forth in the appended claim.

I claim:

1. A method of making a contact element, which comprises

providing a disc shaped subhead of base metal including, on at least one side thereof, a first, substantially planar horizontal surface extending over the major portion thereof, a second, substantially planar horizontal surface disposed vertically below and annularly of said first surface and extending over a minor portion of said side, and a substantially vertical wall member connecting said first and second surfaces;

disposing a segment of precious metal contact face material adjacent said first surface;

heating the assembly to effect melting of the precious metal segment and gravity flow of the molten metal across said first and second surfaces and simultaneously

fusing the molten precious metal to form a contact face of material thickness disposed in juxtaposition

with said first and second surfaces to the periphery of said subhead.
